Fig. 1

Fig. 2

Fig. 3

Fig. 4

FIG. 1 is a top plan view of a cooking vessel showing my new design, with a portion of the vessel being omitted for convenience of illustration;

FIG. 2 is a transverse sectional view, taken along the line II-II of FIG. 1, looking in the direction indicated by the arrows;

FIG. 3 is an end elevational view of the vessel; and FIG. 4 is a side elevational view thereof.

The end and side not shown in FIGS. 3 and 4, respectively, are similar in appearance to the end and side shown.

The dominant features of my invention are shown by the full lines.

I claim:

The ornamental design for a cooking vessel or the like, as shown and described.
